The ornamental design for a test strip packaging, as shown and described.

DESCRIPTION

FIG. 1 is a front perspective view of the test strip packaging completely open.

FIG. 2 is a front view thereof.

FIG. 3 is a back view thereof.

FIG. 4 is a left side view thereof.

FIG. 5 is a right side view thereof.

FIG. 6 is a top view thereof.

FIG. 7 is a bottom view thereof.

FIG. 8 is a front perspective view of the test strip packaging partly open; and,

FIG. 9 is a front perspective view of the test strip packaging completely closed.

The evenly-spaced broken lines are shown for the purpose of illustrating both parts of the article as well as environmental subject matter of an exemplary test strip. The dash-dot broken lines are shown for the purpose of illustrating parts of the article. None of the broken lines form part of the claimed design.
